US0D1113770S

(12) **United States Design Patent** (10) **Patent No.:** **US D1,113,770 S**
(45) **Date of Patent:** **** Feb. 17, 2026**

(54) **COVER PLATE FOR SWITCHES**

(71) Applicant: **AJAX SYSTEMS CYPRUS HOLDINGS LTD**, Nicosia (CY)

(72) Inventors: **Oleksandr Konotopskyi**, Kyiv (UA);
Ilshat Garipov, Haapsalu (EE);
Evgeniya Medvedeva, Kharkov (UA)

(73) Assignee: **AJAX SYSTEMS CYPRUS HOLDINGS LTD**, Nicosia (CY)

(**) Term: **15 Years**

(21) Appl. No.: **29/986,266**

(22) Filed: **Jan. 17, 2025**

Related U.S. Application Data

(62) Division of application No. 35/517,087, filed on Apr. 7, 2023 (U.S. filing date under 35 U.S.C. 384), and having an international filing date of Apr. 7, 2023, now Pat. No. Des. 1,067,203.

(57) **CLAIM**

The ornamental design for a cover plate for switches, as shown and described.

DESCRIPTION

The file of this patent contains at least one drawing/photograph executed in color. Copies of this patent with color drawing(s)/photographs will be provided by the Office upon request and payment of the necessary fee.

FIG. 1 is a perspective view;

FIG. 2 is a front view;

FIG. 3 is a back view;

FIG. 4 is a top view;

FIG. 5 a bottom view;

FIG. 6 is a right view; and,

FIG. 7 is a left view.

The dotted broken lines represent the portions of the cover plate for switches that form no part of the claimed design.

1 Claim, 5 Drawing Sheets
(2 of 5 Drawing Sheet(s) Filed in Color)
